UNITED STATES PATENT OFFICE.

HERMAN SIXBEY, OF MAYVILLE, NEW YORK.

ACCOUNT-BOOK.

SPECIFICATION forming part of Letters Patent No. 758,220, dated April 26, 1904.

Application filed August 13, 1903. Serial No. 169,318. (No model.)

To all whom it may concern:

Be it known that I, HERMAN SIXBEY, a resident of Mayville, in the county of Chautauqua and State of New York, have invented certain 5 new and useful Improvements in Account-Books; and I do hereby declare the following to be a full, clear, and exact description of the invention, such as will enable others skilled in the art to which it pertains to make and use 10 the same.

The invention relates to account, memorandum, or other like books, and has for its object to provide a convenient, efficient, and economical book in which to write accounts 15 or memoranda of any kind and in which the sheets of writing-paper are removable and easily renewable.

The invention consists in the construction hereinafter described and pointed out.

20 In the accompanying drawings, Figure 1 is an end view of the book. Fig. 2 is a plan of one of the sections of the book, comprising a stiff leaf with tablets or bunches of leaves of writing-paper attached, the lower bunch being omitted and the attachment of a bunch on the opposite face of the leaf indicated by broken lines. Fig. 3 is a partial section on line 3 3 of Fig. 2.

Numeral 1 denotes a cover of any suitable 30 or desirable kind and of any convenient size. It may have a flexible back, an ordinary back, or a covered wood or metal back. In the present instance six blocks 1^x are fixed in the back and are connected by means of suitably- 35 attached strips of canvas 4 to three stiff leaves 2, conveniently made of paper-board or equivalent, and to two intermediate leaves 3, preferably made of thinner and lighter material, but thicker than ordinary writing-paper. To 40 the stiff leaves 2 and on each face are secured tablets or bunches of leaves of writing-paper suitably ruled, if desired, for the particular purpose for which the book may be intended, and they may also have any suitable words or 45 figures printed thereon. In the instance illustrated three tablets or bunches of sheets are detachably connected on each side of every stiff leaf 2, and it is proposed to appropriate these, except the last bunch on the back face 50 of the third sheet 2, to groups of letters or to

letters of the alphabet, beginning with the first bunch at the top of the first page of the first stiff sheet and using seventeen bunches in succession. The following grouping and division of the alphabet has been found convenient, to wit: "A B C D," "E F," "G H," "I J K," "L M," "N O," "P," "Q R," "S," "T U V," "W," "X Y Z." The arrangement and appropriation of the bunches to alphabetical groups has been found convenient in using the book as a ledger, but it should be understood that the appropriation of portions of the paper to particular letters is not material and that the invention is not limited to any number of stiff and intermediate 65 sheets nor to any number of bunches of writing-paper nor to any particular use. In the present instance the paper bunches are detachably secured to the leaves 2 by means of wire fasteners 8 bent about the ends 9 of the paper 70 bunches and extended through holes 5 in the leaves or boards 2 near their inner edges or through holes 6 near their outer edges, the wire ends being bent back against the boards to fasten the bunches in place. These holes 75 may be eyeleted, if preferred. The bunches thus attached each to a leaf 2 by wires 8, passing through holes 5 near its inner edge, are situated on the front face of the leaf, and those similarly attached by means of holes 6 are situated on the succeeding face, from which arrangement it follows that in all the bunches the paper will be similarly arranged, so that the writing thereon will be from the left to the right. For convenience the paper of the 85 bunches is provided with dovetail portions 9, about which the wire fasteners are bent, as indicated. The use of other fastening devices, whether made of wire or not, will not be a departure from the main invention. 90

The purpose of the intermediate leaves 3 is to aid in keeping the paper bunches clean and in order, and their use is preferred, though not always essential. In some cases blotting-paper will be found a useful material for said 95 leaves 3.

Although the particular blocks 1^x are not essential, it is important that some means for suitably spacing or separating the stiff leaves be used. 100

The improved book can be used as a price and discount book and also as a salesman's sample book and for other like purposes, and it is also adapted for other than mercantile uses.

5 It may be noted that each sheet of writing-paper can be detached either with or without the detachment of the bunch and also that in cases where the leaves of the bunches have been filled with desired entries made according to 10 any preferred order the bunches may be detached and their separate sheets redistributed in another order. Thus if the entries be made on sheets in duplicate or triplicate or other number the sheets can be easily distributed 15 according to any desired classification, and for this general purpose or other purposes manifolding-paper can be used as circumstances indicate. Single sheets may be detached from the fastened bunch by pulling the 20 dovetail under the wire either with or without folding under the tips 11.

I am aware that supplementary cards and tablets or bunches of leaves have been attached to stiff book-leaves and also that one 25 or more details of my construction have been used heretofore, and I do not broadly claim such devices. My improvement comprises a book having stiff leaves and bunches of leaves 30 detachably connected thereto independently of the book-cover, said bunches having approximately the length of the width of the stiff leaves and connected to both faces of each of the latter adjacent their left edges. The bunches are attached near the inner edge of 35 the left-hand face or page of each stiff cover and near the outer edge of the succeeding page. The bunches on the right-hand face of the leaf being attached near its free edge will upon turning the leaf, as in opening the book, 40 be carried into suitable position for writing thereon. The attachment of bunches to opposite faces or pages of the same leaf also obviates interference of the fastenings. The wire fastenings situated at a considerable distance 45 from the back of the book are distinct from the bookbinding and are conveniently applied to or removed from the bunches, as required. The simple dovetail portion formed at the right end of each bunch, approximately in 50 length the width of the bunch, provides a means of securely holding the sheets of the same. The spacing-blocks being fixed to the back and the stiff leaves being connected to them by flexible material provision is thereby 55 made for space for the bunches or tablets and for easy manipulation of the bunch-laden

leaves, and the whole, comprising the special arrangement of bunches and the particular means for attaching and detaching them, is a practically new article well adapted for uses 60 such as herein suggested.

Having described my invention, what I claim as new, and desire to secure by Letters Patent, is—

1. A book-cover, spacing-blocks fixed to the 65 cover-back, stiff leaves therein secured to the blocks by flexible strips, means for removably securing bunches of ruled or other suitable paper to the stiff leaves, and intermediate leaves, said latter leaves having flexible connection 70 with the spacing-blocks.

2. A book having a stiff leaf provided with holes, a bunch of paper provided at one end with a dovetail portion having a length approximating the width of the bunch, and a 75 wire fastening surrounding said portion and passed through the holes and then bent down upon the leaf, said wire being flexible and independent of the bookbinding whereby the bunch may be detached and either replaced or 80 another substituted and secured by the same fastening without injury to the book.

3. A book having a stiff leaf, bunches of paper secured on said leaf on opposite sides and at opposite edges, each of said edges being 85 situated at the left when the leaf and tablets thereon are suitably disposed for writing.

4. A book having a stiff leaf, bunches of paper secured on said leaf and on opposite sides and at opposite edges, each of said edges being 90 situated at the left when the leaf and tablets thereon are suitably disposed for writing, and intermediate leaves to keep the paper clean and in order.

5. The book having a leaf provided with a 95 detachable bunch of paper comprising a plurality of sheets, and means for connecting the bunch to the leaf, said means consisting of flexible wire bent about the bunch and extended through the leaf, said wire being flexible and 100 independent of the bookbinding whereby the bunch may be detached and either replaced or another substituted and secured by the same fastening without injury to the book.

In testimony whereof I have signed this 105 specification in the presence of two subscribing witnesses.

HERMAN SIXBEY.
